STETHOSCOPE HEAD

David Littmann, Belmont, Mass., assignor to Cardiosonics
Medical Instruments Corporation, Cambridge, Mass.,
a corporation of Massachusetts

Filed June 18, 1965, Ser. No. 85,802

Term of patent 14 years

(Cl. D83—12)

Fig.1

Fig.2

Fig.3

FIG. 1 is a plan view of one face of a stethoscope head showing my new design;

FIG. 2 is a plan view of the face opposite to that shown in FIG. 1; and

FIG. 3 is an edge view looking from either the left or right of FIG. 2.

I claim:

The ornamental design for a stethoscope head, as shown.
